Clifford Gare Sweet INVENTOR

UNITED STATES PATENT OFFICE.

CLIFFORD GARL SWEET, OF SAN DIEGO, CALIFORNIA.

WASHING-MACHINE.

1,389,081.

Specification of Letters Patent. Patented Aug. 30, 1921.

Application filed October 12, 1920. Serial No. 416,518.

To all whom it may concern:

Be it known that I, CLIFFORD GARL SWEET, a citizen of the United States, residing at San Diego, in the county of San Diego and 5 State of California, have invented a new and useful Washing-Machine, of which the following is a specification.

This invention relates to improvements in washing machines and has for an important 10 object thereof the provision of a readily operable, manually operated washing machine, although not necessarily limited to a manual operation as will hereinafter more fully appear.

15 An important object of the invention is to provide in a device of the above character, means for simultaneously reciprocating and rotating a tub containing clothes.

20 A further object of the invention is to provide a device of the above character which employs in conjunction with the mechanism for rotating and reciprocating the tub, a plurality of washing devices of the type known as pounders, together with 25 means whereby the reciprocation of the tub causes the pounders to be reciprocated into and out of the same.

25 A further object of the invention is to provide a machine of this character in which 30 the weight of the tub assists the operator in the operation of cleansing the clothes.

35 A still further object of the invention is to provide a device of this character which is extremely simple in construction and operation and which accordingly is not likely to become broken or destroyed in use.

40 These and other objects I attain by the mechanism illustrated in the accompanying drawings wherein like reference characters designate like parts throughout, and wherein:

Figure 1 is a side elevation of a washing machine constructed in accordance with my invention, parts being broken away;

45 Fig. 2 is a section on the line 2—2 of Fig. 1; and

Fig. 3 is an end elevation taken from the end indicated by the line 3—3 on Fig. 1.

Referring now more particularly to the 50 drawings, the numeral 18 indicates a horse comprising end braces 10 connected at their upper ends by a longitudinal brace 14 and adjacent their lower ends by longitudinal braces 14^a.

55 The ends of the brace 14 project beyond the end braces 10 and have pivotally con-

nected thereto the lower ends of levers 4 and 4^a. To these levers a bed 11 is pivotally connected which is provided at its sides intermediate the end braces 10, with angular extensions 17^a. To the longitudinal braces 14^a of the horse 18, intermediate the end braces 10, are pivotally connected the lower ends of links 17, the upper ends of which are pivotally connected to the extensions 17^a. 60 These links 17 assist in further supporting the bed 11. Upon the upper ends of the links 17 and upon the bed 11, are mounted rollers 8. Extending upwardly from the bed 11 is a support 21 upon which is rotatably 70 mounted a tub support 6, and a ratchet disk 7, secured together for unitary rotation, the disk 7 bearing upon the rollers 8. The tub support 6 is adapted for the reception of a tub 5. 75

Pivots connected to the horse 18 is a dog 9, held in engagement with the ratchet disk 9^a. Upon reciprocation of the bed 11, the dog 9 engaging the ratchet disk 7, causes rotation of the disk, tub support and tub, as 80 will be obvious. To the upper ends of the levers 4 and 4^a I secure suitably braced arms 16^a, to which in turn are adjustably secured clothes pounders 16.

In the operation of my device, when either 85 of the levers 4 or 4^a is engaged by the hand and oscillated, the bed 11 is reciprocated causing the pounders 16 to alternately engage in the tub and the tub to be reciprocated. This reciprocation, as hereinafter set 90 forth, causes intermittent rotation of the tub, resulting in the entire surface being presented to the pounders for the action thereof upon continued rotation. Furthermore, the inertia of the tub, arriving at the 95 end of each stroke, tends to press the pounders 16 very firmly into engagement with the clothes without the necessity of the operator applying great pressure to the levers 4 and 4^a which are engaged. If desired, the reciprocating bed 11 may be provided with an extension 11^a having mounted thereon a 100 seat 12 in which the operator may sit, and a foot-rest 15 may be provided. In order to prevent unnecessary strain upon the extension 11^a, the same may be supported by a member 13 pivotally connected thereto. It will be seen that when seated the operator 105 may assist the action of the arms in operating the washing machine by movements of the lower limbs.

From the foregoing it is believed to be ob-

vious that I have constructed a washing machine which is particularly well adapted for the use for which it is intended by reason of the fact that the operation of the machine is actually assisted by the weight of the tub containing the clothes, and by reason of the fact that the construction thereof is so simple and the device is so easily operated that there is little likelihood of the destruction thereof in use. It will furthermore be obvious that the construction thereof as hereinbefore set forth may readily be connected with suitable power force for reciprocating the bed 11, and that many changes of a similar character may readily be made without in any manner departing from the spirit of my invention, and I accordingly do not limit myself to the specific structure hereinbefore set forth except as hereinafter 20 claimed.

What I claim is:—

1. In a washing machine, a tub support and means for simultaneously rotating and reciprocating said tub support.
2. In a washing machine, a support adapted for the reception of a tub, pounders, means for simultaneously rotating and reciprocating said support and reciprocating said pounders within the tub.
3. In a washing machine, a reciprocatory support, a tub support rotatably mounted

upon said reciprocatory support, and means for rotating said tub support when the reciprocatory support is reciprocated.

4. In a washing machine, a reciprocatory support, a tub support rotatably mounted upon said reciprocatory support, reciprocable pounders operating within the tub, and means for rotating said tub support and reciprocating said pounders when the reciprocatory support is reciprocated.

5. In a washing machine, a stationary support, spaced levers pivotally connected to the support, a bed pivotally connected to the levers and adapted to be reciprocated thereby when the levers are oscillated, a tub support rotatably mounted upon said bed, and means operated by the reciprocation of the bed for rotating said tub support.

6. In a washing machine, a stationary support, spaced levers mounted for oscillation upon said support, a bed pivotally connected to said levers, a roller supported disk rotatably mounted upon the bed, pounders carried by said levers and adapted to operate within a tub carried by said roller supported support, and means operated by the oscillation of said levers for reciprocating said pounders and rotating the last named support.

CLIFFORD GARL SWEET.
